(57) **CLAIM**

The ornamental design for a display screen or portion thereof with transitional graphical user interface, as shown and described.

DESCRIPTION

FIG. 1 is the first image in a sequence for a display screen or portion thereof with transitional graphical user interface showing our new design according to a first embodiment; FIG. 2 is the second image thereof; FIG. 3 is the third image thereof; FIG. 4 is the fourth image thereof; FIG. 5 is the fifth image thereof; FIG. 6 is the sixth image thereof; FIG. 7 is the first image in a sequence for a display screen or portion thereof with transitional graphical user interface showing our new design according to a second embodiment; FIG. 8 is the second image thereof; FIG. 9 is the third image thereof; FIG. 10 is the fourth image thereof; FIG. 11 is the first image in a sequence for a display screen or portion thereof with transitional graphical user interface showing our new design according to a third embodiment; FIG. 12 is the second image thereof; FIG. 13 is the third image thereof; FIG. 14 is the fourth image thereof; FIG. 15 is the first image in a sequence for a display screen or portion thereof with transitional graphical user interface showing our new design according to a fourth embodiment; FIG. 16 is the second image thereof; FIG. 17 is the third image thereof; and, FIG. 18 is the fourth image thereof.

The outer perimeter broken line depicts a display screen or portion thereof and forms no part of the claimed design. The remaining broken lines in the figures depict portions of the transitional graphical user interface and form no part of the claimed design.

The appearance of the transitional image sequentially transitions between the images shown in FIGS. 1-6, FIGS. 7-10, (Continued)

FIGS. 11-14, and FIGS. 15-18. The process or period in which one image transitions to another image forms no part of the claimed design.

The screenshot shows a web-based application interface for financial trading. At the top, a header bar displays 'S8Yam v3M LCH'. Below this, a dark grey bar contains the text 'Cross Submission (0002)'. The main area is titled 'RFC 0007'. It contains several input fields: 'Price' (2.1), 'Payer Brokerage' (0), 'Size' (1), 'Receiver Brokerage' (0), 'Payer' (jpmkt 1), and 'Receiver' (jpmkt 2). To the right of these fields is a 'Submit Cross' button. The entire interface is framed by a dotted border.

Fig. 9

This screenshot shows the same web-based trading interface as Fig. 9, but with a different tab selected. The header bar still displays 'S8Yam v3M LCH'. Below it, a dark grey bar contains the text 'Cross Submission (0002)'. The main area is titled 'RFC 0008'. The input fields are identical to Fig. 9: Price (2.1), Payer Brokerage (0), Size (1), Receiver Brokerage (0), Payer (jpmkt 1), and Receiver (jpmkt 2). To the right is a 'Submit Cross' button. Above the input fields, a tab labeled 'Amounts' is visible, indicating the current active tab. The entire interface is framed by a dotted border.
